**COMBINED DIAL AND HANDS FOR A CLOCK
OR SIMILAR ARTICLE**

John W. Rademacker, Humboldt, Iowa

Application April 15, 1957, Serial No. 45,735

Term of patent 14 years

(Cl. D42—1)

Figure 1 shows a frontal elevation of a combined dial and hands for a clock or similar article showing my new design; and,

Figure 2 is a side elevational view thereof as seen from the right-hand side of Figure 1.

The essential features of the design reside in the portions shown in full lines.

I claim:

The ornamental design for a combined dial and hands

for a clock or similar article, substantially as shown and described.
